INFORMATION DISPLAY BOARD FOR RACE TRACKS

Nicholas A. Grande, Rockville Centre, N.Y., assignor to
Westbury Electronics Corporation, Westbury, N.Y., a
corporation of New York

Filed Sept. 15, 1966, Ser. No. 3,884

Term of patent 3½ years

(Cl. D96—12)

FIG. 1 is a front perspective view of an information display board for race tracks showing my new design; FIG. 2 is a rear elevational view thereof;

FIG. 3 is a face view of one end thereof;

FIG. 4 is an enlarged fragmentary front elevational view thereof; and

FIG. 5 is an enlarged perspective view of a portion of the information display board.

The dominant features of my design reside in the portions shown in full lines, the numeral lights have been omitted in FIGS. 1 and 5 for the convenience of illustration.

I claim:

The ornamental design for an information display board for race tracks, substantially as shown and described.
